BY *Maurice Leo*
ATTORNEYS

UNITED STATES PATENT OFFICE.

SAMUEL BUN CLAYTON, OF GREENSBORO, NORTH CAROLINA.

AUTOMOBILE LOCK.

Application filed September 15, 1922. Serial No. 588,412.

To all whom it may concern:

Be it known that I, SAMUEL B. CLAYTON, a citizen of the United States, and a resident of Greensboro, in the county of Guilford, 5 and State of North Carolina, have invented certain new and useful Improvements in Automobile Locks, of which the following is a specification.

This invention relates to an improvement 10 in automobile locks of the type forming the subject-matter of my prior Patent Number 1,895,906.

The object of the invention is to provide a locking device of this character which is 15 adapted for use with various types of steering mechanism and in which the lock mechanism is embodied in the lock itself and is housed and protected without in any way impairing the universal capabilities of the 20 lock, the device being at the same time of simple and durable construction, reliable in operation and easy and comparatively inexpensive to manufacture.

Other objects and advantages of the in- 25 vention reside in certain novel features of the construction, combination and arrangement of parts which will be hereinafter more fully described and particularly pointed out in the appended claims, reference be- 30 ing had to the accompanying drawings forming part of this specification, and in which:

Figure 1 is a perspective view, showing the preferred embodiment of the invention;

35 Figure 2 is a view, partly in longitudinal central section and partly in elevation, the parts being shown in different positions in dotted lines; and

Figure 3 is a view in transverse section 40 through the body portion, parts being shown in elevation for the sake of illustration.

Referring to the drawings, the numeral 10 designates the body portion of the frame of the lock which is provided with marginal 45 flanges 12, the purpose of which will hereinafter more fully appear. At one end the body portion 10 is provided with a locking slot 13 which extends entirely through the body portion.

50 A yoke designated generally at 15, is provided and includes an arm 16 offset, as at

17, from the body of the yoke and pivotally and reversibly mounted on the side flanges 12 of the body portion 10, this mounting of the yoke being effected by pivotally connecting the arm 16 to a block 18 as indicated at 19 and by pivotally mounting the block 18 on the side flanges, as indicated at 20, the block 20 being rotatable in a plane at right angles to the plane of rotation of the arm 16 and the axis of rotation of the arm and block being spaced from each other, as clearly shown in Figure 2. The yoke 15 also includes a locking arm 21, the outer end portion of which is adapted to be received in the locking slot 13. This arm 21 is in the form of a straight flat bar and may be entered or introduced into the slot 13 from either side or end thereof, as indicated by full and dotted lines in Figure 2. The portion of the locking arm 21 which is disposed within the slot 13 is provided with a transverse opening, designated at 22, and constituting a bolt seat or socket in either position of the yoke.

The locking mechanism is embodied in the body portion 10 and accordingly the body portion 10 is provided with a longitudinally extending bore 23 in which a bolt 24 is mounted for sliding movement. The bolt 24 is adapted to be projected across the slot 13 and into the seat 22 of the locking arm when the locking arm is received in the slot 13 or the bolt 24 may be retracted entirely within its bore 23. A compression coil spring 25 is arranged in one end of the bore and one end of this coil spring engages the adjacent end of the bolt 24, the other end of the coil spring abutting a plug 26 threaded into the bore 23. The compression coil spring 25 is of course under compression and tends to project the bolt, as shown in Figures 2 and 3. A key controlled or permutation lock 27 is provided for controlling the bolt 24, this lock 27 being fitted into a cavity 28 machined or otherwise formed in the body portion 10 and communicating with the bore 23. The lock 27 may be of any known type or design and preferably includes a rotatable barrel 29 which carries a crank pin 30 operatively engaged with a notch 31 formed in the bolt 24 so that as the key is turned

in the lock a crank pin 30 will be turned and will impart a sliding movement to the bolt 24.

A swinging arm 35 is pivotally mounted upon a pin 36 extending transversely between the side flanges 12 and the outer end of the swinging arm 25 is beveled as at 37 and is engaged with the offset portion 17 of the yoke, as shown in Figure 2. This arm 35 serves to restrict the internal area of the yoke when such restriction is desired. A removable pin 38 extends transversely between the flanges 12 of the body portion and has screw threaded connection with one or more of these flanges so that it is releasably held in position. This pin 38 is located so that it engages the swinging arm 35 and holds the same in desired position.

With the parts arranged as shown in Figure 1, the lock is adapted for use with a "J-Cox" type of steering gear in accordance with the showing of my prior patent, the internal end of the yoke being restricted for this purpose by means of the arm 35 in the present instance. If it is desired to adapt the lock for use with the type of steering gear used on "Dodge" automobiles the pin 38 is removed and the arm 35 is swung to the position shown in dotted lines in Figure 2 and then the pin 38 is replaced to hold the arm 35 in the dotted line position. The yoke however is not reversed but is left in its normal or original position that is in the position shown in full lines in Figures 1 and 2. By shifting the pin 35 however the internal area of the yoke has been enlarged sufficiently to enable the yoke to encompass the drag link and the spindle and third arm of the steering gear of a "Dodge" automobile. If it is desired to use the lock upon the type of steering gear used on a "Ford" automobile, the swinging arm 35 is disposed in the dotted line position but the yoke 13 is reversed with respect to the body, as shown in dotted lines in Figure 2 so that the locking arm 21 enters the slot 13 from the opposite side. With the parts so arranged the front axle and adjacent parts of the steering mechanism are embraced by the yoke and held from operation.

In all of the uses of the invention the lock may be applied to the steering mechanism or taken therefrom by an authorized person without undue effort or inconvenience. In applying the lock it is only necessary to properly embrace the parts with the yoke and snap the arm 21 into engagement with the bolt, the end of the locking arm being beveled, as at 21^a, to facilitate this automatic locking. It is to be understood of course that the bolt 24 may also be double beveled at one end to further facilitate the locking action, if desired. To release the lock it is only necessary to insert a key in the slot of the barrel and turn the same

through a revolution or a part of a revolution, as such turning of the key will retract the bolt and permit withdrawal of the locking arm from the bolt. Moreover the device may be readily adapted for use with either the types of steering mechanism as has been previously described.

Although I have herein shown and described only one form of lock embodying my invention it is to be understood that various changes in the form, proportion and minor details of construction may be resorted to without departing from the spirit of the invention and the spirit and scope of the appended claims.

I claim:

1. An automobile lock of the character described comprising a body portion having a locking slot at one side extending entirely through said body portion, a yoke including a pair of arms, one of said arms being pivotally and reversibly connected to said body portion at the side thereof remote from said locking slot and the other of said arms constituting a locking arm and being adapted to be entered into either end of said locking slot, the portion of said locking arm received within said locking slot having an opening therethrough constituting a bolt seat irrespective of the manner in which the locking arm is entered into said locking slot and locking means carried by said body portion and including a bolt engageable with the bolt seat of the locking arm in either position of the yoke.

2. An automobile lock of the character described comprising a body portion having a locking slot open in either side thereof, a yoke reversibly and pivotally mounted on said body portion and having a locking arm adapted to be entered into said locking slot from each side thereof, and locking means carried by the body portion and including a bolt engageable with a portion of the locking arm received in said locking slot.

3. An automobile lock of the character described comprising a body portion having spaced side flanges, a yoke associated with the body portion, a swinging arm mounted on the side plates and having its ends adapted to engage a portion of the yoke for restricting the internal area thereof, said swinging arm being adapted to be moved to such position as not to diminish the effective internal area of the yoke and a pin releasably connected with the side plates and engageable with the swinging arm for holding it in either of its two positions.

4. An automobile lock of the character described including a body portion, a yoke associated with the body portion and a swinging arm adapted to be moved into engagement with the yoke to restrict the internal area thereof.

5. An automobile lock of the character

described, comprising a body portion having a locking slot, a yoke pivotally and reversibly connected to the body portion and having a locking arm adapted to be received in said locking slot, the portion of the locking arm received in the locking slot being provided with a bolt seat and locking

mechanism carried by the body portion comprising a spring projected sliding bolt engageable with the bolt seat of the locking arm and key controlled means for retracting said bolt. 10

SAMUEL BUN CLAYTON.
